UNITED STATES PATENT OFFICE.

PERCY B. CAMP, OF MAYWOOD, ILLINOIS, ASSIGNOR TO UNIVERSAL DRAFT GEAR ATTACHMENT COMPANY, A CORPORATION OF ILLINOIS.

BRAKE MECHANISM FOR RAILWAY CARS.

Application filed January 28, 1924. Serial No. 689,044.

To all whom it may concern:

Be it known that I, PERCY B. CAMP, a citizen of the United States of America, and resident of Maywood, county of Cook, and State of Illinois, have invented certain new and useful Improvements in Brake Mechanism for Railway Cars, of which the following is a specification, and which are illustrated in the accompanying drawings, 10 forming a part thereof.

This invention relates to brake mechanisms for railway cars and has for its object broadly to permit the slack to be taken up quickly and the brakes to be applied with 15 great pressure by hand power.

A further object of the invention is to provide a speed and power multiplying attachment for the conventional brake mechanisms such as is found on hopper cars, 20 which attachment can be supplied at low cost and can be easily and quickly applied to the car by unskilled labor.

Further objects and advantages of the invention will become apparent as the disclosure proceeds and the description is read in connection with the accompanying drawings illustrating selected embodiments of 25 the invention and in which

Fig. 1 is a fragmentary side elevation of 30 a hopper car and its brake mechanism, with one form of attachment applied thereto, the brakes being shown released;

Fig. 2 is a similar view with the brakes applied;

Fig. 3 is a fragmentary plan view partly 35 illustrating the attachment;

Fig. 4 is a perspective view of the bail forming part of the attachment;

Figs. 5 and 6 are views similar to Figs. 40 1 and 2 showing an alternative form;

Fig. 7 is a plan view of the multiplying lever and the jaw or bracket forming part of the attachment,

Figs. 8 and 9 are fragmentary elevations 45 illustrating a construction especially suited for cars where the clearance is small;

Figs. 10 and 11 are similar views illustrating a construction having special advantages when the invention is applied to new 50 cars;

Fig. 12 is a sectional view taken on the line 12-12 of Fig. 11, and

Fig. 13 is a diagram of the attachment applied to a conventional form of inside 55 brake to be found on hopper cars.

In Figs. 1 and 2 of the drawing a fragment of a car underframe is shown at 10 carrying a hopper body 11, the inclined wall of which appears at 12. The brake cylinder 13 is suitably supported on the frame 60 and has a push rod 14 pivoted to the cylinder lever 15, at 16. The cylinder lever has its upper end pivoted to a bracket 17 and its lower end is connected with the brakes through the brake rod 18. The brake staff 65 19 is suitably mounted adjacent to the end of the car frame. All these parts may be of the usual or any preferred form.

In applying the attachment the brake rod 18 is equipped with a special jaw or 70 bracket 20 which is connected to the cylinder lever by a pin 21. Between the sides 22 and 23 of the bracket a multiplying lever is pivoted on the fulcrum pin 24. This lever has two arms 25 and 26, which for 75 convenience, will be designated as staff arm and anchor arm respectively. The staff arm has a relatively long drum surface 27 of large diameter that is connected at one end with a short drum surface 29 of small diameter by what may be called the leading face of the arm 28. A staff chain 30 has one end in winding engagement with the brake staff and extends over the surface of the arm 25 to a suitable shackle 31 at the rear face of 80 the arm. The anchor arm 26 has a relatively long drum surface 32 of less diameter than the drum surface 27 of the staff arm, and this surface is arranged opposite to a portion 33 of relatively long radius. This latter portion is connected with one end of an anchor chain 34, the opposite end of which is anchored to the brake step or the like, by a shackle 35.

The arms 25 and 26, or some parts of 95 them, are preferably arranged to take advantage of the fact that a point traveling in a circle will, in some arcs move principally in one direction, while in other arcs, they will move principally in another direction. 100

When the brakes are released the parts take a position in which the point 36 on the staff arm will first move principally in a direction transverse to the pull on the staff chain 30 and, therefore, a very short movement of chain will produce a wide angle of rotation of the multiplying lever and quickly throw it to a position approximating that shown in Fig. 2 where the leverage of the staff arm is greatly increased. Sim- 105 110

ilarly, the point 37 on the anchor arm first moves in the direction principally parallel to the pull on the anchorage and therefore a small movement of the chain 30 operates 5 to quickly take up the slack as well as to shift from mechanical disadvantage to mechanical advantage by changing the lengths of the corresponding levers.

The normal position of the parts when 10 the brakes are released takes care of any slack in the chain 30 and the bail 38 supported by the pin 21 serves to hold up the back of the anchor chain 34.

In the alternative form shown in Figs. 15 5, 6 and 7 the special jaw or bracket 20 is dispensed with and the usual jaw 39 serves to connect the brake rod 18 with the cylinder lever 15 in the customary manner. The multiplying lever is carried by a 20 bracket or jaw 40 secured to the lever just above the jaw 39. This bracket is provided with cheek plates 41 which straddle the cylinder lever and are secured thereto by a pin 42. The multiplying lever is journaled 25 on pin 43 supported in the side arms 44, which are connected together by an arched brace 45. The staff and anchor chains 30 and 34 are arranged as in the other form, except that the staff chain passes on one 30 side of the cylinder lever and through the arch of the brace 45, and the anchor chain passes below the bracket 40 and on the opposite side of the cylinder lever.

With this form of attachment it is ad- 35 vantageous to have the winding engagement of the staff chain with the brake staff at a slightly higher point and for that reason an upturned bracket 46 may be fitted to the car underframe and form the bottom bearing 40 for the staff. Preferably in both forms the brake staff is provided with a tapered winding cam 47 to constrain the chain to wind upwardly around the staff. This tends to keep the staff chain substantially 45 horizontal and give the full benefit of the long leverage afforded by the staff arm 25.

In Fig. 5 the upper end of the cylinder lever is pivoted to a brace 48 instead of to the bracket 17, as illustrated in Fig. 1, but 50 this is a matter of selection.

In Figs. 8 and 9 the arms 56 and 57 of the multiplying lever are spaced apart by a bearing portion 58 that runs against the cylinder lever 15 and takes the thrust. In this 55 case the multiplying lever is supported by forked bracket 59, secured to the cylinder lever at 60 and having arms 61 between which the lever is journaled on a pin 62.

In Figs. 9, 10 and 11, the arms 63 and 64 60 of the multiplying lever are carried by a shaft 65 having a cylindrical portion 66 journaled in the lever 15 and non-circular portions 67 and 68 receiving the arms 63 and 64. The non-circular portion 68 is il- 65 lustrated as being tapered and the arm 64

is forced thereon by a nut 69 which may be locked with a cotter pin 70. A strap 71 secured to the lever at 72 is perforated at 73 to receive the opposite end of the shaft which may be also equipped with a cotter 70 pin 74.

The brake rod 18 is connected with one end of the lever 49, (Fig. 8) the opposite end of which is connected by rod 50 with the live lever 51 which, in turn, is connected 75 by the thrust rod 52 with the dead lever 53 and the brake beams 54, and brake shoes 55 are arranged in the usual or any preferred manner.

The invention permits the ordinary brake 80 mechanism, such as found on hopper cars, to be readily converted into a device that will quickly take up the slack and then forcibly apply the brakes by hand power applied to the brake staff. It permits the 85 multiplying device to be conveniently placed so as not to limit the range of the equipment. However, while the invention is particularly adapted for use in connection with hopper cars, it is also capable of other uses 90 and may be embodied in other forms. I, therefore, do not wish to be limited except as is made necessary by the prior art.

I claim as my invention:

1. In a brake mechanism for railway cars, 95 the combination of a car underframe, a hopper body having an inclined bottom, a cylinder lever pivotally mounted between said inclined bottom and the underframe and having one end projecting below the latter 100 and connected with the brakes, a brake staff, a multiplying lever having a staff arm and an anchor arm on opposite sides of the plane of the cylinder lever, means for rotatably mounting the multiplying lever on the opposite side of the cylinder lever from the 105 brake staff and connecting it with the cylinder lever, a chain connecting the staff arm and the brake staff and a chain connecting the anchor arm with an anchorage on the car 110 frame.

2. In a brake mechanism for railway cars, the combination with a brake staff and a cylinder lever, of a multiplying lever rotatably mounted on the opposite side of the 115 cylinder lever from the brake staff and co-operating therewith through a thrust connection, said multiplying lever having staff and anchor arms on opposite sides of the plane of the cylinder lever, a staff chain 120 connecting the brake staff and the brake arm and an anchor chain connecting the anchor arm and an anchorage.

3. In a brake mechanism for railway cars, the combination with a brake staff and a 125 cylinder lever, of a bracket secured to the cylinder lever and projecting away from the brake staff, a multiplying lever rotatably mounted in said bracket and having staff and anchor arms on opposite sides of the 130

plane of the cylinder lever, a staff chain connected with the staff arm and in winding engagement with the brake staff and an anchor chain connecting the anchor arm with an anchorage.

4. In a brake mechanism for railway cars, the combination with a brake staff and a cylinder lever, of a multiplying lever rotatably mounted on the cylinder lever and 10 having staff and anchor arms on opposite sides of the plane of the cylinder lever and arranged to take advantage of the fact that a point traveling in a circle will in some arcs travel principally in one direction and 15 in other arcs will travel principally in a different direction, a staff chain connecting the brake staff and the brake arm and an anchor chain connecting the anchor arm and an anchorage.
- 20 5. In a brake mechanism for railway cars, the combination of a car underframe, an inclined floor of a hopper body, an upright cylinder lever having its lower end connected with the car brakes, a brake staff, a rigid 25 thrust member connected with the cylinder lever, a multiplying lever journaled in said thrust member and including a staff arm and an anchor arm arranged on opposite sides of the plane of the cylinder lever and 30 chains connecting the respective said multi-

plying lever with the brake staff and an anchorage.

6. In a brake mechanism for railway cars, the combination of a car underframe, a cylinder lever connected with the car brakes, 35 a brake staff, a rotatably mounted multiplying lever carried by the cylinder lever and having a staff arm provided with a long drum surface of large diameter and a short drum surface of small diameter and an anchor arm provided with a drum surface of less diameter than the long drum surface of the staff arm, a staff chain cooperating with the staff arm and in winding engagement with the brake staff, and a brake chain 40 connecting the anchor arm with an anchorage, said arms and chains being arranged on opposite sides of the plane of the cylinder lever. 45

7. In a brake mechanism for railway cars, 50 the combination of a car underframe, a brake staff, a cylinder lever, a rotatably mounted multiplying lever carried by the cylinder lever and having a staff arm and an anchor arm arranged on opposite sides 55 of the plane of said cylinder lever and chains connecting said arms with the brake staff and an anchorage respectively.

PERCY B. CAMP.
